HEEL PULLEY BLOCK HOLDING DEVICE

Application filed August 2, 1929. Serial No. 383,116.

My invention relates to improvements in heel pulley block holding devices and the object of my invention is to provide simple, efficient and reliable friction means for holding a pulley block in a predetermined elevated position.

The invention is shown and described as applied to a heel block of the form commonly used at the foot of a boom in cargo handling apparatus but is obviously adapted for use in connection with substantially any swiveled pulley block.

In the operation of the usual heel blocks of cargo handling apparatus, and of other swiveled pulley blocks of similar nature, where the cable which passes over the block is, at times, drawn through the block in a slack condition, it is obvious that, when the cable is slack, the pulley block will be caused by gravity to hang down in a position in which the cable will not lead fair over the pulley but will rub against the side of the block thus wearing both the block and the cable before sufficient tension is exerted on the cable to lift the block into the proper position. To overcome this difficulty in connection with heel blocks, which are used at the foot of booms, on cargo handling apparatus, it has heretofore been common practice to hold up the outer end of the block by means of a piece of rope or chain tied to the boom and to the heel block or to stretch a cable across the ship and support the outer end of the heel block from this cable by means of a runner pulley. Both of these methods are a makeshift and require constant adjustment and are in the way and tend to foul and chafe the main cable and are totally inoperative for some positions of the boom.

Another method of holding the heel block up has been to square or flatten the end of the swivel eye so that it will abut against the hanger and form a positive stop. This method is objectionable because it does not provide for the proper adjustment and results in a rapid deterioration of the swivel.

It is an object of my present invention to overcome the difficulties hereinbefore set forth by providing a heel block which is equipped with adjustable friction means for

adjustably holding said block in any desired position, said friction means being capable of supporting the weight of the block and cables but being arranged to yield in the event a strain is placed on the block to permit the block to automatically assume a position in which the cable will lead fairly over the block.

More specific objects are to provide a pulley block embodying a forked hanger arranged to receive and pivotally support a swivel member to which a pulley is connected, said block having adjustable friction means embodied in the pivotal connection between the hanger and the swivel means.

Other and more specific objects will be apparent from the following description taken in connection with the accompanying drawing.

In the drawing Figure 1 is a perspective view of a heel pulley block constructed in accordance with my invention showing the same in an operative position in connection with a spar and boom of the form used for handling cargo, fragments only of the spar and boom being shown;

Fig. 2 is a detached plan view on a larger scale of the heel pulley block mounting, parts of the pulley frame being broken away;

Figs. 3 and 4 are detached elevations of the forked mounting plate and pivot bolt respectively of the device shown in Fig. 2;

Fig. 5 is a plan view of an alternative form of heel pulley block mounting in which the resilient spring means is omitted from the friction device; and

Fig. 6 is a plan view of another alternative form of heel pulley block mounting in which a tapered bearing pin is used for obtaining the friction.

Referring to the drawing, throughout which like reference numerals designate like parts, I show a pulley block mounting embodying a forked hanger 7 having two spaced apart, forwardly extending, parallel side plates or arms 8 and 9, provided respectively with a larger hole 10 constituting a bolt head receiving eye, and a smaller hole 11 constituting a bolt shank receiving eye. The holes 10 and 11 are disposed in axial alignment.

and are arranged to receive a pin 12. The rear end of the hanger 7 has a transverse hole 13 extending in a direction at right angles to the common axis of the holes 10 and 11. Said rear end of said hanger 7 is adapted to fit between two lugs 14 and 15 of a supporting bracket 16 which may be secured to a mast 17. An upright pin 18 passes through suitable holes in the lugs 14 and 15 and 10 through the hole 13 in the hanger 7 and forms a vertical pivot on which the hanger may swing. The upper end of the pin 18 preferably terminates in an eye portion 19, which in the installation shown in Fig. 1, may be 15 connected by a bolt 20 with a plate 21 on the lower end of a boom 22 so that the vertical pin 18 constitutes a pivot for the boom 22 to swing on.

The head of the bolt 12 is freely movable 20 within and through the larger hole 10 in one side of the clevis and said hole 10 and the bolt head are suitably shaped to prevent the bolt from turning. One method of preventing turning of a cylindrical bolt head in a 25 cylindrical hole is to form a notch or key seat 23 in one side of the hole 10 and provide a lug or dowel 24 on the bolt head to fit into the notch 23.

The side plates 8 and 9 of the hanger are 30 spaced apart for the reception therebetween of a swivel member 25 and two or more washers or plates 26 and 27. The bolt 12 has a lug 28 adjacent its head, which fits into a notch 29 in the washer 26 and prevents relative 35 turning movement between the washer 26 and the bolt. This makes it impossible for turning movement to occur between the inner end of the bolt head and the washer, with consequent loss of friction and excessive 40 wear, as would be the case if these two parts were not locked together.

The bolt 12 projects beyond the side 9 of the hanger and has a relatively heavy compression spring 30 thereon. A nut 31 on the 45 end of the bolt adjustably supports the outer end of the spring 30. The threads on the bolt 12 are preferably in one direction, as right hand, and the coil of the spring 30 in the opposite direction, as left hand, so that 50 the action of the spring will not tend to unscrew the nut 31.

The outer end of the swivel member 25 has a shank 25' forming a swivel connection with a block 32 within which is journaled a pulley 55 or sheave 33 over which passes a cable 34. The upwardly extending end of the cable 34 will usually pass over a sheave, not shown, at the upper end of the boom 22 and the lower end of said cable will ordinarily be connected 60 with a winch or winding drum, not shown.

The operation of the friction is as follows: The pressure of the spring 30 against the nut 31 draws the head of the bolt 12 tightly against the washer 26 thus frictionally 65 clamping together the washer 26, eye mem-

ber 25, washer 27 and hanger part 9. This holds the sheave block in any elevated position in which it is placed and prevents it from hanging down when the cable is slack. At the same time the sheave block is free to 70 turn on the shank 25' of the swivel member and the clevis 7 is free to turn about the vertical pivot 18.

For any particular setting of the boom 22 there will be one proper elevated or inclined 75 position of the block at the foot of the boom and that position will be such that the longitudinal center line of the block will lie in the line of the resultant of the forces exerted by the cable 34 in leading onto and off the sheave 33, the same usually being the bisector 80 of the angle formed by the cable. It is evident that the block frame 32 is free to swing on the swivel shank 25' and on the vertical pin 18 but the incline of the longitudinal axis of the block will always remain substantially the same for each setting of the boom. The friction of the clutch is sufficient to hold up the weight of the heel block and cable but 90 the heel block is selfadjusting to the pull of the cable.

Where the pulley block is not to be used for a relatively long period of time, the nut 31 may be loosened to relieve the tension of the 95 spring 30.

In Fig. 5 I show an alternative form of the invention in which the spring 30 is dispensed with and the bolt 12 is made shorter and is provided with a nut 35 which bears directly against the outer side of the hanger member 8. The nut 35 is prevented from turning by suitable locking means, as a lock nut 36. The operation of this device is substantially the same as the operation of the device disclosed in Figs. 1 to 4, except that 100 it is necessary to accurately adjust the nuts at more frequent intervals to secure and maintain the desired tension.

In Fig. 6 I have shown another alternative 105 construction in which the swivel eye member 37 is provided with a conical hole indicated at 38 and a bolt 39 having a conically tapered portion 40 is arranged to fit within said tapered hole. The head end 41 of the bolt 39 may be square or hexagonal and may fit within a similarly shaped hole in the side of the hanger member. A washer 42 is provided between the eye member 37 and the other side of the hanger and means, as a 110 spring and nut are provided for exerting a tension on the bolt 39. In this form of the invention the contacting sides of the hanger and the washer 42 and the eye member 37 together with the interfitting cone portions 38 and 40 constitute the friction surfaces which 115 tend to hold the block in any desired elevated position.

Obviously, changes may be made in the 120 forms, dimensions and arrangement of the 125 130

parts of my invention, without departing from the principle thereof, the above setting forth only preferred forms of embodiment.

I claim:

- 5 A pulley block holding device embodying a bracket; a hanger having a bifurcated end portion with a bolt shank receiving hole in one arm of said bifurcated end, a bolt head receiving hole in the other arm; means pivotally engaging the end of the hanger, opposite the bifurcated portion, to the said bracket for horizontal movement; a bolt slidably mounted in the said holes in the bifurcated end portion of the hanger, having 10 means on said bolt head engaging the hanger and preventing turning of the bolt; a pulley block swivel member pivotally mounted upon said bolt for vertical movement; a washer member non-rotatably secured upon said bolt 15 and disposed between said swivel member and said bolt head; another washer member disposed between the swivel member and one of the arms of said bifurcated portion of the hanger; a compression spring on said bolt on 20 the outside of said last named bifurcated arm; and a nut on said bolt retaining said compression spring under pressure, whereby said swivel member is frictionally disposed as respects one arm of said bifurcated hanger 25 30 and said non-rotatably mounted washer, thereby permitting the swivel member to be yieldingly held in any desired position of its vertical travel.

In witness whereof, I hereunto subscribe
35 my name this 29th day of July, 1929.

ALVIN R. CAMPBELL.
